UNITED STATES PATENT OFFICE.

MORRIS W. KELLOGG, OF NEW YORK, N. Y., AND EMIL F. HOLINGER, OF JERSEY CITY, NEW JERSEY, ASSIGNEES TO THE M. W. KELLOGG COMPANY, A CORPORATION OF DELAWARE.

APPARATUS FOR MAKING FORGINGS.

Application filed February 5, 1920. Serial No. 356,506.

To all whom it may concern:

Be it known that we, MORRIS W. KELLOGG and EMIL F. HOLINGER, citizens of the United States, and residing, respectively, in the city, county, and State of New York, and Jersey City, county of Hudson, State of New Jersey, have invented certain new and useful Improvements in Apparatus for Making Forgings, of which the following is 10 a full, clear, exact, and concise description.

The object of our invention is to produce forgings for large hydraulic fittings and similar parts made of steel, iron or similar strong metallic material without the necessity of hammering or pressing the same into shape by the usual methods employed in connection with the art of forging by the use of steam or air hammers or by the method known as drop forging. This invention relates primarily to the manufacture of articles which are hollow and consists mainly of metallic shells of steel or similar material, such as those comprising pipe or hydraulic fittings already referred to, 25 although it is not limited thereto.

Briefly stated, our invention comprises the shaping of a billet or blank of steel or similar material into the required form by the use of a die or matrix carried in a strong, 30 preferably integral, die holder and into which the billet or blank is introduced. Said billet contained in said die is forced into the required shape by high hydraulic pressures operating upon suitable plungers or punches, thus causing the material to flow from the center outward in substantially radial directions and to fill or conform to the contour or shape of the die or matrix. These punches or piercing tools 35 enter the hot plastic material from various directions, depending upon the shape of the article being forged, so that the flowing of the metal is substantially uniform. For a detailed description of one embodiment of 40 our invention which we deem at present preferable, reference may be had to the following specification and to the accompanying drawings forming part thereof, in which—

50 Fig. 1 is a sectional elevation of a table or platen, and illustrates the progressive movements of the die or matrix thereon during the various steps of the process;

Fig. 2 is a sectional plan view of the 55 same;

Fig. 3 is a vertical sectional view, substantially on the line A—A, Fig. 2, showing the parts as arranged during the last step of the process; and

Fig. 4 is an elevation of a finished valve 60 body made according to our process.

Referring to Fig. 1, the numeral 1 indicates the die or matrix which is preferably made in two symmetrical parts as indicated. The interior shape or contour of this die is 65 the same as the form desired to be given to the valve body or casing, or other fittings to be made therein. The two halves of the die or matrix 1 are placed on the lower level of the platen or bed of the apparatus, as indicated by the numeral 2. By means of a hydraulic or steam actuated plunger 3, the matrix 1 is pushed toward the left until it rests on the elevating platform 4 operated by the plunger 5. The two halves of the 70 die are now pushed up through an opening in the platen 6 until the same enters the die holder 7 which is located over said opening. This die holder 7 is attached to a horizontally reciprocating rod or bar 8 operated 75 by hydraulic or steam pressure or otherwise as it may be considered preferable. This rod or bar 8 is next moved in the direction of the arrow thereby drawing the die holder and die contained therein to a 80 position beneath the vertical plate 9, as indicated in Figs. 1 and 2. This position of the die holder 7 is also opposite a trough 85 shown most clearly in Fig. 2 and which supports the heated billet or blank 11 to 90 be operated upon. The latter is then pushed through an opening 12 in one end of the die holder until it rests centrally within the die itself. Thereafter, the vertical stopping-off plate 9 having a hole 13 is dropped 95 into a similarly shaped recess, or opening, in the die holder 7. The die holder and die are next moved further toward the left until the same are placed below the punch or piercing tool 14 operated hydraulically or in 100 any other suitable way, by a suitable cylinder located above the same, but not shown, and which is supported by the upright bars or posts 15. Located laterally on each side of the last position of the die holder and die, horizontal punches or piercing tools 16 are provided, also operated hydraulically in any suitable way. These piercing tools 14 and 16 are then caused to move under heavy hydraulic pressure into the die holder 105

110

and die and thereby cause the material of the billet to flow outward and fill the spaces in the die provided to give the required shape. The exact sequence in which these punches or piercing tools enter the die should be determined according to the shape and size of the article being formed, different articles requiring different movements of these tools, that is, as regards whether 10 their movements are simultaneous, successive, step by step, or continuous and independently progressive.

Fig. 3 indicates the third and last step of the process just referred to, the piercing tools 16 being indicated as partly withdrawn from the finished article or valve casing.

To remove the forged article from the die, the movements of the die and die holder are reversed until the die reaches its original position on the lower portion of the platen at 20 2, where the die is opened and the article withdrawn.

It should be understood that the apparatus above described is not adapted to a process like that known as "die casting" in which 25 small metallic parts made of soft metal are manufactured rapidly and accurately by hydraulic pressure but on the other hand is designed for making large pipe fittings and 30 similar articles made from steel and similar hard metals of high tensile strength.

Having thus described this form of our invention, we do not wish to be understood as being limited to the details above set forth, 35 for many variations may be made therein, without departing from the spirit and scope of our invention.

What we claim and desire to protect by Letters Patent is:

40 1. Apparatus for forging hollow articles from steel and similar materials, which comprises a suitable hollow die, a die holder directly contacting with the die on opposite sides to prevent the separation of the parts 45 thereof, means for introducing a blank into said die, said die and die holder having a plurality of openings therein to receive suitable piercing tools, and means for expanding said blank within said die when in said 50 holder comprising a plurality of piercing tools or punches adapted to enter said openings and advance to the center of said die.

2. Apparatus for forging hollow articles, from steel and similar materials, which 55 comprises a suitable die made in a plurality of separable parts, a die holder encircling and directly contacting with the same on opposite sides to prevent the separation of the parts thereof, means for introducing a blank 60 into said die, said die and die holder having a plurality of openings therein to receive suitable piercing tools, and means for expanding said blank within said die when in said holder comprising a plurality of piercing 65 tools or punches adapted to enter said

openings and advance to the center of said die.

3. Apparatus for forging hollow articles from steel and similar materials, which comprises a suitable hollow die, a die holder 70 adapted to enclose the same except on one side thereof and prevent separation of the parts thereof, means for inserting a billet into said die, means for expanding a billet in said die comprising piercing tools or 75 punches, said die and die holder having a plurality of openings therein to receive said piercing tools and an opening to receive a stopping off plate, and a stopping off plate having an opening therein to receive one of 80 said tools.

4. Apparatus for forging hollow articles from metal, which comprises a bed, a die holder on said bed having an opening in its bottom, a die, means for introducing said 85 die into said holder, and means for moving said holder along said bed from the point for introducing the die therein to a point where said bed supports the bottom of the die in the holder. 90

5. Apparatus for forging hollow articles from metal, which comprises a bed, a die holder on said bed having an opening in its bottom and an opening in one side for introducing a billet, means for introducing a 95 die into said holder, means for introducing a billet therein, means for expanding a billet in said die, and means for moving said holder, die and billet along said bed to the position for acting on said billet by said 100 expanding means, said bed supporting said die while said expanding means are operating on said billet.

6. Apparatus for forging hollow articles from metal, which comprises a bed, a die 105 holder on said bed having an opening for introducing a die therein, means for introducing said die at a definite point on said bed, means for expanding a billet in said die in said holder, said expanding means 110 being spaced from said introducing means along said bed, and means for moving said holder along said bed from one of said means to the other.

7. Apparatus for forging hollow articles 115 from metal, which comprises a bed, a die holder on said bed having an opening in its bottom for introducing a die into the holder, said holder having apertures therein for introducing a billet into the die in the holder 120 and apertures through which expanding means may operate on said billet, a means for introducing a die into said holder at a definite point on said bed, means for introducing a billet into said die in said holder, 125 means for expanding said billet in said die, said die introducing means, said billet introducing means and said expanding means being placed at different points along said bed, and means for moving said die holder 130

from one of said means to the other as desired.

8. Apparatus for forging hollow articles from steel and similar materials comprising
5 a divided die, a die holder encircling said die and contacting therewith directly on four sides to prevent separation of the parts of the die during the forging operation, said die and die holder having a plurality of openings therein to receive suitable tools, one of said openings being adapted to receive a blank or billet, a stopping off plate for said last mentioned opening, and means
10 for expanding a billet in said die comprising a plurality of piercing tools adapted to enter said openings and advance to the center of said die.

- 15 9. Apparatus for forging hollow articles from steel and similar materials comprising

a divided die, a die holder encircling said die and contacting therewith directly on four sides to prevent separation of the parts of the die during the forging operation, said die and die holder having a plurality of openings therein to receive suitable tools, one of said openings being adapted to receive a blank or billet, a stopping off plate for said last mentioned opening, and means
20 for expanding a billet in said die comprising a plurality of piercing tools adapted to enter said openings and advance to the center of said die.
